CLAIM

The ornamental design for a faucet, as shown and described.

DESCRIPTION

FIG. 1 is a perspective view of a faucet of the present invention.

FIG. 2 is another perspective thereof.

FIG. 3 is a front view thereof.

FIG. 4 is a rear view thereof.

FIG. 5 is a left view thereof.

FIG. 6 is a right view thereof.

FIG. 7 is a top view thereof; and,

FIG. 8 is a bottom view thereof.

The broken line showing of certain portions of the faucet is included for the purpose of illustration only and forms no part of the claimed design.
